UNITED STATES PATENT OFFICE

2,613,117

CONVEYER BELT SUPPORTING MECHANISM

Arthur L. Lee, Upper Arlington, Ohio, assignor to
The Jeffrey Manufacturing Company, a corpora-
tion of Ohio.

Original application March 8, 1945, Serial No.
581,630, now Patent No. 2,592,915, dated April
15, 1952. Divided and this application July 26,
1947, Serial No. 763,822

10 Claims. (Cl. 308—20)

1

This invention relates to belt conveyers, and more particularly to mechanism which supports the traveling belt thereof.

An object of the invention is to provide improved simplified conveyor belt supporting mechanisms that are extremely flexible and rugged, yet relatively inexpensive.

A further object of the invention is to provide improved construction for intermediate sections of the belt conveyor frame including improved idler stand construction, and improved chair construction.

A further object of the invention is to provide improved mechanism for training both the working and return runs of the conveyor belt, or either of them, individually.

Still another object of the invention is to provide improved mechanism for training the return idlers of the intermediate sections of the conveyor while also providing for their ready removal and insertion.

Still another object of the invention is to provide improved idler and idler supporting mechanism.

A further object of the invention is to provide an improved bearing assembly for the belt idler and to provide an improved bearing assembly and associated supporting and thrust taking mechanism.

Other objects of the invention will appear hereinafter, the novel features and combinations being set forth in the appended claims.

In the accompanying drawings,

Fig. 1 is a perspective view of an intermediate section of an endless conveyor, including two chairs and associated idler stands;

Fig. 2 is an enlarged side elevational view of a chair and associated idler stand of the intermediate section shown in Fig. 1 with interconnected pans of the conveyor frame and a portion of the associated belt;

Fig. 3 is an enlarged sectional view taken on line 3—3 of Fig. 2, looking in the direction of the arrows;

Fig. 4 is an exploded view of the intermediate section of the endless belt conveyor shown in Fig. 1, also showing an associated chair and idler stand together with the connecting pan, in perspective;

Fig. 5 is a transverse sectional view with certain parts also shown in section along different planes showing particularly the chair, idler stand and associated pan of the intermediate section of the conveyor shown in Fig. 1;

Fig. 6 is an enlarged sectional view through

2

the supporting bracket of one of the idler bearing assemblies, with the bearing assembly and part of the associated pan shown in elevation;

Fig. 7 is a view taken along the line 7—7 of Fig. 5, looking in the direction of the arrows; and

Fig. 8 is an enlarged sectional view of a ball bearing assembly and associated structure.

This application is a division of my application, Serial No. 581,630, filed March 8, 1945, now Patent No. 2,592,915, dated April 15, 1952, for Improvements in a Chair and Idler Roll Stand Assembly for Conveyors.

It is to be understood that the construction and operation of the conveyor of this application follows that of my parent application, above identified, and that only the subject matter pertinent to this application is discussed in detail herein.

Referring to Fig. 1 of the drawings there is shown a portion of an endless belt conveyor. The head and tail section of the conveyor, of which the portion shown forms a part, may be constructed in any suitable manner but preferably they are constructed as shown and described in my parent application, above identified, wherein the conveyor includes a head or drive section, a foot or tail section, and a plurality of intermediate sections 23 shown herein, the number of which may be varied to provide a conveyor of variable length. The head section of the conveyor may include suitable belt driving and takeup pulleys and the tail section of the conveyor includes a foot or tail pulley about which the endless belt 28 of the conveyor is reeved to form a top or working run and a bottom or return run. The top or working run of the belt 28 between the head and foot or tail pulleys is carried by a plurality of troughing idlers or rolls 77, 79 and the bottom or return run of belt 28 is carried by a plurality of return idlers or rolls 52. The frame of the conveyor includes the frames of the head and tail sections and an intermediate sectional frame portion connecting the head and tail section frames which is constructed of the frame parts of each intermediate section 23, as herein-after fully described.

Attention is now directed to the drawings and to the construction of the intermediate section 23 and the constituent parts thereof. The intermediate sections 23 are built up of a plurality of spaced apart similar chair and idler or roll stand assemblies 43 which are of similar construction and the principal parts of each of

50 55

which are a chair 44 and an idler or roll stand 45.

Interconnecting adjacent chair assemblies 43 and holding them in proper spaced relation and alignment, while providing for a certain amount of flexibility in their relative vertical positions, is an interconnecting frame member in the form of an inverted U-shaped pan 46, the structure of which is described in detail hereinafter.

Each chair 44 is formed of a U-shaped structural steel member having a generally horizontal flat cross-piece or cross plate 47 with a downwardly extending or upright leg or plate 48 at each end thereof, each leg 48 being provided with a pair of ground engaging feet 49. The feet 49 and adjacent portions of the leg 48 are preferably provided with reinforcing depressions or indentations 50. The legs 48 and associated construction on each side of the transverse cross-piece 47 are of similar construction. Each leg or plate 48 includes a centrally disposed opening 51 which is of sufficient size to provide for extending a return idler or roll 52 therethrough, which return idler 52 is supported by the chair 44 in a manner hereinafter described, and which supports the return run of the belt 28 and also provides for training of said return run of the belt.

Adjacent each opening 51 is an adjustable bracket assembly 53 which provides for the removable supporting of the adjacent end of the return idler 52 and also provides for adjustment of said supported end forwardly and rearwardly relative to the direction of travel of the belt 28 in a horizontal plane, or, in other words, provides for training adjustment of said idler 52.

The bracket assembly 53 includes a longitudinally extending generally U-shaped strap or plate 54 forming wings having elongated slots 55 adapted to receive nuts and bolts 56 which attach said wings of the strap 54 to the plate or leg 48 on opposite sides of the opening 51 and adjacent thereto. Elongated slots 55 provide for the training adjustment of the bracket assembly 53, since they provide for forward and rearward adjustment of one end of the return idler 52 which is supported by said bracket assembly 53.

The inner edges of the strap or plate 54 are sheared and bent out to provide guide tabs 57 which act as guides and abutting means for a pivoted U-shaped bracket 58, at the upper and inner portion of which there is a U-shaped bearing or supporting member 59 which receives and supports a bearing assembly 60 of the idler 52, there, of course, being duplicate bearing assemblies 60 on opposite ends of a hollow live shaft 61 (see Fig. 5) of the idler 52; the ends of the shaft 61 being welded to the ends of a cylindrical roller 62 of said idler 52. The shaft 61 extends beyond the ends of the roller 62 and is supported by the bearing assembly 60 in a manner similar to that hereinafter described in connection with the troughing idlers.

The bracket or plate 58 also includes a square opening or hole 63 which receives a squared projection on the bearing assembly 60 and thus holds said bearing assembly 60 against rotation. This squared projection is also preferably provided with a grease fitting 64 by which the bearing of the bearing assembly 60 is lubricated.

At its bottom, the bracket or plate 58 is provided with an elongated pivotal opening 65 (see Fig. 3), which receives a pivot pin 66 rigidly attached to cross-piece 47. A similar member 70

connected to and extending between a pair of spaced outwardly extending wings 67 formed on the bottom of the strap or plate 54. The top of the bracket or plate 58 is provided with a pair of spaced lugs or hooks 68 (see Fig. 3), there being one adjacent each edge and on opposite sides of the U-shaped member 59, the lugs or hooks 68 being adjustable so that they can be lifted over and then moved downwardly to form an interlocking relation with inward projections of the strap or plate 54 relative to opening 51, as clearly illustrated in Fig. 3 of the drawings.

The normal assembled relation of the parts of the bracket assembly 53 is illustrated in Figs. 1, 2 and 3 of the drawings, for example, and it is to be noted that the co-operating relation between the hooks 68 and projecting portions of the plate or strap 54 holds the U-shaped bracket 58 in a position to receive and support the idler 52 through the bearing assembly 60. Opposite ends of the idler 52 are supported by the two similar bracket assemblies 53 and bearing assemblies 60. The relation of parts provides a self-aligning type of bearing in a manner which is described more completely hereinafter, in connection with troughing idlers.

The training effect of the idler 52 may be adjusted by adjusting the bracket assembly 53 on either or both of the legs 48 of the chair 44. This of course, is effected by loosening the nuts 56, after which adjustment they are tightened to clamp the bracket assemblies 53 in position. An idler 52 may be removed from either side of the chair by the simple expedient of first lifting upwardly on the bracket or plate 58, then lifting the hooks 68 free of the projecting portions of strap or plate 54, as provided by the elongated pivotal opening 65. Thereupon, the bracket 58 may be swung downwardly and outwardly, as illustrated in Fig. 7 of the drawings, and the idler 52 can be moved outwardly as suggested in said Fig. 7, wherein an idler 52 is shown laterally of a chair 44.

The hollow construction of shaft 61 of the idler 52 also provides for lubricating the bearings of both bearing assemblies 60, by applying grease to one of them. This may be desirable, particularly where only one of the grease fittings 64 is readily accessible. This is also described more completely in connection with the troughing idler roller, and it is to be understood that the fundamental relation between the roller and bearing assembly of the return idler 52 is the same as that of each troughing idler. Each bracket 58, of course, not only supports the associated bearing assembly 60, but also takes any end thrust on the idler 52.

Referring particularly to Figs. 1 and 4 of the drawings, it will be seen that upon each chair 44 and forming a part of the assembly 43, is an idler or roll stand 45. Furthermore, intermediate each chair and stand assembly 43 and supported by an interconnecting pan 46 is a similar idler or roll stand 45. Each roll stand 45 includes an inverted U-shaped base or channel 69 which is adapted to rest on the cross-plate 47 of a chair 44 or on top of an inverted U-shaped pan 46.

The channel 69 extends over and is directly attached to and guided by an inverted U-shaped idler stand guiding and chair reinforcing member 70 which has feet or wings on the bottom thereof, which are welded or otherwise rigidly attached to cross-piece 47. A similar member 70

is provided substantially at the center of each pan 46 to receive the associated idler stand 45, and to reinforce said pan 46.

In view of the channel shape of the base 69 it obviously will fit over the member 70 and the ledges provided by the feet thereof will act as guides to provide alignment of the idler stand 45 on the cross-piece 47, or the pan 46, as the case may be. However, adequate clearance is provided between the upright webs of the base or channel 69 and the ledges provided by the feet of the cross-member 70, so that the longitudinal axis of the base or channel 69 may be angularly adjusted with respect to the longitudinal axis of the member 70. This provides for manual adjustment of the angle of the base 69 with respect to the axis of movement of the belt 28, thus providing for training action on said belt 28.

The opposite ends of the U-shaped members 70 are provided with open slots 71 through which bolts 72, provided with large square heads 73, extend, which square heads 73 co-operate with the side walls of the members 70 to prevent rotation of the bolts 72. The bolts 72 extend through elongated slots 74 and receive clamping nuts 75. The elongated slots 74 provide the training adjustment of the idler stands 45 above mentioned.

The idler stands 45 also include a pair of similar or complementary end brackets 76 which support the outer and upper ends of inclined troughing idlers 77, the inner and lower ends of which are supported on spaced brackets 78. In addition, a center or horizontal idler 79 is provided, which is supported on spaced brackets 80; all of the brackets above mentioned being mounted on the base 69, with the last mentioned brackets spaced laterally from the others, relative to the axis of said idler stand 45.

Except for the inclined relation of the idler rollers 77, produced by the fact that the brackets 76 are longer than the brackets 78, the important structure of the brackets 76, 78 and 80 is similar.

In Figs 5 and 8 of the drawings I have illustrated in some detail the structure of the idler 79 and the associated bracket 80 which constitute important contributions of the invention. Said idler 79 includes a cylindrical roll 81 with integral heads or ends which are welded or otherwise permanently attached to a transversely extending hollow shaft 82. In other words, the hollow shaft 82 is a live shaft and rotates with the roll 81. The shaft 82 extends along its own axis beyond the opposite heads of the roll 81, forming projections which receive, for example, as by a relatively tight fit, the inner race 83 of a ball bearing assembly designated generally by the reference character 84.

The ball bearing assembly 84 is identical in construction to the previously mentioned bearing assembly 68. It includes a series of precision balls 85 which ride on the inner race 83 and within an outer race 86. The ball bearing formed by the inner and outer races 83 and 86 and the balls 85 is essentially of standard ball bearing construction, except that the outer periphery of the outer race 86 is crowned or is a segment of a sphere.

The ball bearing 83-86 is mounted in a casing or housing 87 which is preferably formed of mild pressed steel, the casing or housing being open at one side and receiving a grease seal 88 which closes the opening of the casing in co-operation with the rotating inner race 83.

The outer race 86 and casing or housing 87

are, of course, stationary, and the outer end of the casing 87 includes an integral head or plate 89, at the center of which is a boss or projection 90 which has square sides extending into a U-shaped bifurcated clip 91 which co-operates with said square boss or projection 90 to prevent rotation of the bearing assembly 84. Furthermore, as best illustrated in Fig. 6 of the drawings, the prongs of the clip 91 are preferably curved at their points of contact with the head or plate 89 of casing 87, thus providing a rolling contact therewith.

Furthermore, said spaced points of rolling contact between the prongs of clip 91 and said head or plate 89 lie in a plane which passes through the axis of the shaft 82, or, in other words, through the axis of the idler 79, or of the idlers 77, as the case may be. It is thus evident that axial thrusts of the idlers 77 or 79 are taken by the bifurcated clips 91 along their axes and thus there is no rotating moment which tends to cause twisting or rotating of the bearing assemblies 84 in planes at right angles to their axes.

The squared sides of the projections or bosses 90 also serve an additional purpose. Said projections or bosses 90 are provided with grease fittings 92 which provide for lubrication of the bearings 83-86. As clearly illustrated in Fig. 6 of the drawings, the receiving nipple of these projections extends at an angle to the axis of the bearing assembly 84, and this nipple may extend to any one of four different angles, depending upon how the projection 90 is received by the prongs of the clip 91. The grease fitting will be held in any position to which it is thus adjusted.

By referring again to Figs. 5 and 8 of the drawings, it will be seen that at the center portion the head or plate 89 is close to, but slightly spaced from, the adjacent face of the inner race 83. This performs two functions. First of all, it provides a path or way which offers some resistance or is restricted to the flow of grease which is delivered to the central portion of the casing or housing 87 through the fitting 92 and boss 90, so that the grease will not all flow to this immediate bearing, but a portion of it will flow through the central bore or passageway provided by the hollow shaft 82 and thus flow to the interior of the other bearing assembly 84 on the other end of the shaft 82. This is particularly important where, as in some instances, only one of the grease fittings 92 of any idler, is readily reached for lubrication. An illustration of this, of course, is found in the inclined idler 77, since the inner bearing assemblies are not readily reached for lubrication.

The structure above described also performs another very important function. In view of the flexibility of the integral head or plate 89 which is inherent in its structure and material, it will readily deflect under force, and thus it is possible, by putting a pipe or fitting over the boss 90, to apply pressure through the head 89 directly on to the inner race 83 without appreciable force traveling through the balls 85 which might cause brinelling. This is of particular importance in assembling a bearing assembly 84 on the exposed portion of a shaft 82, as it is desirable that the inner race 83 have a reasonably tight fit with said shaft 82.

Attention is now directed to the mounting of the bearing assemblies 84. The portion of the casing 87, which is in close contact with the crowned outer surface of the outer race 86,

provides an outer bearing surface which is substantially a portion of a sphere, for example, a portion which might result from cutting a sphere by two spaced parallel planes equidistant from the major diameter thereof. In other words, if a plane were passed substantially through the center of the balls 85, it would cut a circle. If a plane were passed through the axis of the shaft 82 which is the same as the axis of the idler 77 or 79 and the axis of the bearing assembly 84, this plane would cut the housing 81 and on the top and bottom it would be along an arc which is preferably an arc of a circle, though it need not be so, provided it has a somewhat arcuate surface. The section of the bearing assembly 84, seen in Fig. 5, is taken along such a plane.

Thus, this bearing surface which is essentially a segment of a sphere and which is designated 93, will have a rolling contact with a co-operating U-shaped receiving portion 94 of the brackets 76, 78 or 80, as the case may be. In other words, insofar as said receiving portion 94 is concerned, it is the same on each of the brackets 76, 78 and 80.

This U-shaped receiving portion is generally flat, as viewed in section in a plane passing through the axis of shaft 82 or idler 77 or 79, as the case may be. It is obvious, of course, that the bearing surface provided by the receiving portion 94 may, if desired, be made convex in the inclined plane, and the bearing surface 93 might be made substantially cylindrical and produce a similar result. The important characteristic is that one of these surfaces should be convex relative to the other, as viewed in any plane through the axis thereof, thus to provide a rolling contact between the two bearing surfaces 93 and 94.

Also, as best illustrated in Fig. 7 of the drawings, the peripheral contacts between the bearing surfaces 93 and 94 extends over an area which is preferably substantially 180° and is desirably at least 90° in extent.

In Fig. 7 of the drawings, the clearance provided for the insertion and removal of the bearing assembly 84 in the receiving portion 94 of bracket 76, has been slightly exaggerated.

The structure of each bearing assembly 84 and co-operating supporting and end thrust taking structures is of considerable importance. First of all, the bearing surface 93 has a large radial angle of contact with the supporting surface 94 and thus it will not become grooved, flat, or unduly worn. At the same time, the bearing assembly 84 is held against rattling in the associated bracket, since the contact between the bearing surfaces 93 and 94 extends preferably over 180°.

It has been found in practice that irregularities in manufacture quite generally produce some cyclic oscillation of portions of the bearings. In many such devices, where the inner and outer races of the bearings are held rigid, this produces binding and undesirable friction. In my arrangement, the bearing surface 93 is free to roll, as required for each cycle of operation, on the bearing surface 94, thus eliminating any undesirable binding or friction during operation. Furthermore, since the inner race of the bearing is the one that rotates, and since its peripheral diameter is less than that of the outer race, it is obvious that the frictional drag inherently produced by the rotation of the balls of the bearing will be a minimum and will be less than that

where the outer race is the rotating one, and the inner race the stationary one. Still further, since the axial thrust is taken along a plane passing through the axes of the idlers, there will be no twisting effect on the bearing assemblies 84.

The rollers, bearings and the supports therefor as well as the self-aligning features provided thereby are claimed in my co-pending application, Ser. No. 704,783, filed October 21, 1946, now Patent No. 2,554,037, dated May 22, 1951, for a belt conveyer.

Referring now to Figs. 1, 4 and 5 of the drawings, it will be seen that each of the U-shaped pans 46 includes a rolled reinforcing bead 95 adjacent its bottom edge and at each end is provided with a pair of spaced holes 96 each adapted to receive and extend over a pin or projection 97 on the chair 44. It is obvious that each chain 44 will have four pins 97, one adjacent each corner of the cross-piece 47 thereof, and that the opposite ends of each pan 46 will be supported on adjacent chairs and held there by a pair of pins 97.

Furthermore, adjacent each end, the pan 46 is provided with a U-shaped reinforcing and wear strap 98 which is welded or otherwise rigidly attached to the inner face of said pan 46 adjacent each end.

To provide a smooth contour between the edges of the pans 46 and the chairs 44, for example, as best illustrated in Fig. 2 of the drawings, each chair is recessed at its opposite sides, both on the cross-piece 47 and on a portion of each leg 48, to receive the strap 98 and the end portion of each pan 46; these recesses being designated 99. Also both the top and side portions of each recess 99 are provided with depressions or indentations 100 which reinforce these portions of the chair 44 and also act to provide smooth or rounded surfaces which may be contacted by the top or the edges of the return run of the belt 28. In other words, this prevents the return run of the belt 28 contacting sharp or cutting edges and thus prevents damage being done to it.

From the above description, it is obvious that elements of the intermediate sections 23 of the belt conveyer may be broken down into a great many small parts and this is of importance in the transportation of intermediate sections, since they may be laid on top the belt and delivered to the point where they are to be used. In the drawings and in the preferred embodiment of the invention, the pans 46 are shown as one piece pans. If desired, however, they may be split down the middle or may be split into three parts, including a central portion and two side parts. If any such splitting is done, it may be desired to employ additional pins or projections 97, to the end that each portion or at least each outside portion will have two pins holding it to each chair 44.

It is further obvious that I have provided a belt conveyer intermediate section construction in which both the working and return runs of the belt may be trained. Furthermore, it is possible to remove an idler stand 45 and all its idlers, while other idler stands on opposite sides thereof are supporting the belt. For example, the idler stand 45 supported by pan 46, may be removed, while the belt 28 is supported by idler stands on the chairs 44, or vice versa.

It is, of course, obvious that each individual idler 77 or 79 may be removed and replaced by

the simple expedient of lifting it upwardly out of its supporting bracket. Also any return idler 52 may be removed from either side of the chair by swinging its supporting bracket 52 downwardly and removing the idler 52 through an opening 51. The other features of the belt conveyer are believed evident from the previous description thereof.

It will also be obvious that I have provided an idler roll assembly and bearing therefor wherein the bearing is substantially a sealed unit that is adapted to be pressed upon the idler roll shaft by pressure applied to the head, plate, or outer shell of the bearing and that during the pressing operation the outer shell of the bearing will deflect against connector race of the bearing to transfer the applied pressure directly to the inner race of the bearing thereby eliminating the danger of brinnelling of balls and races of the bearings.

It will also be obvious that the proximity of the outer shell to the inner race of the bearing provides a restriction through which lubricant must pass to reach the balls of the bearing and that this restriction causes lubricant to be forced when the bearings are being lubricated through the hollow live shaft of the roll to the opposing bearing thereby insuring that lubricant reaches the balls of both bearings.

Obviously those skilled in the art may make various changes in the details and arrangement of parts without departing from the spirit and scope of the invention as defined by the claims hereto appended, and I therefore wish not to be restricted to the precise construction herein disclosed.

Having thus described and shown an embodiment of the invention, what I desire to secure by Letters Patent of the United States is:

1. A belt idler mechanism including a roller and a live hollow shaft rigidly attached thereto, spaced anti-friction bearing means for opposite ends of said shaft including inner and outer races, separate housings for said spaced bearing means, and means for lubricating one of said bearing housings direct, said hollow live shaft communicating with the housing of the other bearing to communicate lubricating material thereto which is fed to said one bearing housing, said one housing being formed near the inner race of the adjacent bearing to restrict the flow of lubricating fluid to its bearing which is fed to said one housing thereby encouraging it to flow to said other bearing housing through said live hollow shaft.

2. A belt idler mechanism including an anti-friction bearing having inner and outer races, and a one-piece pressed steel casing for said bearing, said casing having an outer portion receiving said outer race and provided with an outer wall closing one side of said casing, said closing outer wall being close to but spaced slightly from the inner race and being deflectable under pressure to contact said inner race, whereby pressure near the center of said closing wall may be transmitted to said inner race directly through said wall.

3. A belt idler mechanism including an anti-friction bearing having inner and outer races, and a one-piece casing for said bearing, said casing having an outer portion receiving said outer race and provided with an outer wall closing one side of said casing, said closing outer wall being close to but spaced slightly from the inner race and being deflectable under pressure

to contact said inner race, whereby pressure near the center of said closing wall may be transmitted to said inner race directly through said wall.

5. A belt idler mechanism including a roller having end heads and a hollow live shaft extending axially therethrough, said hollow live shaft projecting through and being rigidly attached to said end heads to rotate with said roller, spaced anti-friction bearing means on opposite ends of said hollow live shaft, said anti-friction bearing means each including an inner race adapted to be pressed onto the end of said hollow live shaft and an outer race, and a separate casing for each of said spaced anti-friction bearing means each having a one-piece pressed steel casing including a generally cylindrical portion receiving said outer race and having close contact over substantially the entire outer surface thereof, said generally cylindrical portion having an outer bearing surface formed as a segment of a generally spherical surface and at one side receiving a grease seal which cooperates to enclose one side of the anti-friction bearing, said casing at the other side forming a plate having a central squared projection, said spherical surfaces and said squared projections being adapted to be received by bracket means cooperating with said squared projections to prevent rotation of said outer race and cooperating with said spherical surfaces to support said roller, said plate portion of said casing being slightly spaced from an adjacent face of the inner race and providing a restricted way through which grease must flow from said squared projection to reach said anti-friction bearing, said restricted way encouraging grease applied under pressure to the adjacent squared projection to flow through said hollow live shaft to the other bearing means.

4. A bearing assembly including an inner race adapted to be pressed onto a shaft, an outer race, a one-piece pressed steel casing for said bearing including a cylindrical portion receiving said outer race, and a side forming plate having a central squared projection adapted to receive a grease fitting, said squared projection being adapted to be received by bracket means cooperating therewith to prevent rotation of said casing on the bearing axis, said plate portion being slightly spaced from an adjacent face of the inner race and providing a restricted way through which grease must flow from said squared projection to reach said bearing and being deflectable against the adjacent face of said inner race whereby said race may be pressed onto said shaft by pressure applied through said plate portion.

6. A bearing assembly including an inner race adapted to be pressed onto a shaft, an outer race, and a one-piece pressed steel casing for said bearing including a cylindrical portion receiving said outer race and a side forming plate having a central squared projection, said squared projection being adapted to be received by a bracket means cooperating therewith to prevent rotation of said casing on the bearing axis, said plate portion being slightly spaced from an adjacent face of the inner race and being deflectable against the adjacent face of said inner race whereby said race may be pressed onto said shaft by pressure applied through said plate portion.

7. A belt idler mechanism including an anti-friction bearing having inner and outer bearing races and a pressed steel one-piece casing for

11

said bearing including a portion formed generally as a segment of a sphere directly receiving said outer bearing race, said generally spherical portion of said casing forming an outer bearing surface adapted to be received directly in a 5 mounting bracket, said one-piece casing including an integral closure on one side having a projection extending axially therefrom adapted to receive a grease fitting and to be engaged by means for preventing axial rotation of the casing 10 with respect to its mounting bracket.

8. A belt idler mechanism including an anti-friction bearing having inner and outer bearing races and a pressed steel one-piece casing for said bearing including a portion formed generally as a segment of a sphere directly receiving said outer bearing race, said generally spherical portion of said casing forming an outer bearing surface adapted to be received directly in a mounting bracket, said one-piece casing including an integral closure on one side having a projection extending axially therefrom adapted to be engaged by means for preventing axial rotation of the casing with respect to its mounting bracket.

9. A one-piece pressed steel casing for a bearing including a portion adapted to receive said bearing and formed generally as a segment of a sphere, said generally spherical portion of said casing forming an outer bearing surface adapted 30 to be received directly in a mounting bracket,

5
10

and said one-piece casing including an integral closure on one side having a projection extending axially therefrom adapted to receive a grease fitting and to be engaged by means for preventing axial rotation of the casing with respect to its supporting bracket.

10. A one-piece pressed steel casing for a bearing including a portion adapted to receive said bearing and formed generally as a segment of a sphere, said generally spherical portion of said casing forming an outer bearing surface adapted to be received directly in a mounting bracket, and said one-piece casing including an integral closure on one side having a projection extending axially therefrom adapted to be engaged by means for preventing axial rotation of the casing with respect to its supporting bracket.

ARTHUR L. LEE.
